JACQUARD MECHANISM AND TEXTILE
MACHINE EMPLOYING SUCH MECHANISM

Harry Goodley, Nottingham, England

Application May 18, 1936, Serial No. 80,451
In Great Britain August 13, 1935

7 Claims. (Cl. 96—20)

This invention comprises improvements in or relating to jacquard mechanism and textile machines employing said mechanism, and has particular, although not exclusive, reference to lace curtain machines.

The type of jacquard mechanism to which the invention refers is that which functions through the medium of contact elements at the jacquard electrically to control the selective operation of thread-controlling and/or patterning elements in the machine in which the jacquard mechanism is installed. According to my prior Patent No. 1,984,128, jacquard mechanism functions selectively to energize and de-energize electromagnets and by so doing selectively control the motion of thread-controlling or patterning elements, e. g. pickers or jacks, in the machine; means being also embodied whereby the motion imparted to the pickers, i. e. the degree to which same are projected between the spool, warp and/or other threads, is adjustably and variably determined according to the dictates of the pattern or weave of fabric to be produced.

The electrical control as above of the pickers of a lace curtain machine renders unnecessary the employment of the numerous and lengthy strings which it is customary to provide extending from the jacquard lifters or needles to the pickers through sleys, which strings are affected by variable temperatures or atmospheric conditions and require constant care and frequent attention and adjustment if good work is to be produced. Also by dispensing with the use of the lengthy strings it is unnecessary to locate the jacquard mechanism high above the machine, and consequently the necessity of a lofty room for housing the machine is avoided.

As is well known it is customary to manufacture on lace curtain machines fabric of considerably different widths, and the size of the jacquard cards and consequently also of the jacquard mechanism employed varies in accordance with the width and gauge of the machine. Now the customary string type of jacquard embodies a number of card-engaging needles corresponding to the number of pickers or jacks in the machine, and if it is required to make fabric having a plurality of divisions say 40 inches wide on the machine, each division has to be punched in the cards, thereby necessitating long cards. The present invention, however, provides means whereby this duplication in the cards is obviated and enables any number of divisions to be made on the machine with cards punched for one division only. The said means enables cards

of a minimum size to be employed on machines of different widths in the manufacture of fabric of different widths, thereby effecting very considerable saving in the cost of material for the cards and in the punching thereof. Also the amount of space required for the storage of jacquard cards is reduced to a minimum due to the reduction in the size of said cards.

To this end an important feature of the invention consists in the provision of jacquard mechanism for use in a textile machine, e. g. a lace curtain machine, functioning by contact elements associated with the jacquard electrically to control the selective operation of thread controlling and/or patterning elements in the machine, and having in combination therewith an electric current distribution device functioning to permit operation of a number of thread controlling or patterning elements in excess of the number of contact elements at the jacquard.

Another object of the present invention is generally to improve the construction and arrangement of pattern control mechanism in a textile machine, and particularly a lace curtain machine, of the type set forth in the aforesaid prior patent, so as to increase the operative efficiency of the machine, and in particular to ensure at all times positive and instantaneous operation of the electromagnets influencing the thread-controlling elements (pickers).

According to another feature of the present invention the selective energization of magnets from a jacquard controls or varies the motions imparted to selected or predetermined thread-controlling elements (e. g. pickers), and the control by said magnets is released when the magnets are de-energized. In other words, the selective energization of magnets causes parts or elements associated with said magnets to be moved into engagement with members (e. g. notched bars) associated with the pickers or the like, and the de-energization of said magnets permits said elements or parts to move or be displaced by gravity or otherwise out of engagement with said notched bars. In this manner positive and instantaneous engagement between the magnet elements and the notched bars or the like is assured. Means are also provided whereby a more effective contact is made between the contact pins of the jacquard and contact plates or members at said jacquard.

The invention also includes improved and positive means for returning the several pickers or the like to their normal (inoperative) position after each motion of the machine, that is to

say after said pickers have been operated upon by the usual picker cam.

For the purpose of more fully describing the nature of this invention reference will now be made to the accompanying drawings, wherein:—

Fig. 1 is a general view illustrating somewhat diagrammatically in part-sectional elevation the application of the present invention to a lace curtain machine.

10 Fig. 2 is an enlarged sectional view showing more clearly the electrical control of the magnets from the jacquard through a distributing device, the latter being shown in sectional plan for the sake of clearness.

15 Fig. 3 is a plan view of the lower part of Fig. 2. Figs. 4 and 5 are sectional details, enlarged, showing two types of contacts for the jacquard.

20 Figs. 6, 7, and 8 are detail sectional views illustrating three positions of a picker and the means associated therewith for controlling its movements.

Fig. 9 is a detail view illustrating an alternative form of one of the controlling magnets.

25 A convenient method of carrying out the invention will now be described as applied to a lace curtain machine having jacquard mechanism intermittently racked in the customary manner, a chain of perforated jacquard cards being passed over the jacquard cylinder or each 30 of same.

35 The jacquard cylinder 1, or each of same, is perforated in the customary manner, and at each turn of the cylinder a predetermined number of jacquard pins 2 project through perforations in the cards into said cylinder. The jacquard pins are slidably mounted within blocks 3 of insulating material, a light coiled spring 4 associated with each pin 2 serving as a cushion element when the pin is pressed back into the block. Each pin 2 at its forward or projecting 40 end has a nose portion 2a of reduced cross-sectional area so as to provide an annular shoulder or contact face 2b at the junction between said nose and the main body of the pin. Between the 45 forward ends of the pins and the jacquard cylinder is provided a metal contact plate 5 conveniently mounted to have a slidable parallel movement towards and away from the cylinder 1 by providing said plate with laterally projecting 50 arms 6 slidable within supporting brackets 6' secured to the aforesaid pin-carrying block 3. The contact plate 5 is provided with perforations equal in number to the contact pins 2 and the 55 perforations 1a in the jacquard cylinder 1, and in one arrangement the reduced nose portions 2a of the contact pins are of insulating or non-conducting material as in Fig. 4. Alternatively the perforations in the contact plate 5 may be 60 lined with fibre or other insulating material 7 (Fig. 5) for receiving said reduced ends or noses of the contact pins. Each pin is electrically connected by insulated wire 8' to one or more electro-magnets 8 and with each magnet is associated a slidably displaceable notched bar 9 or 65 the like which is in turn connected to a resilient picker or jack 10 advantageously of the customary type; the pickers being operated upon by a rotary cam 11 of the usual design functioning to 70 project said pickers through the warp and spool threads of the machine, (Fig. 1).

75 The selection of the pickers 10 to be projected between the threads is electrically effected by the aforesaid electro-magnets 8, it being understood that there is preferably a notched sliding

bar 9 and magnet 8 for each picker; the operation being as follows.

When a jacquard cylinder 1 has been rotated and is moved towards the block 3 carrying the contact pins 2, the aforesaid perforated contact 5 plate 5 (which is normally spaced from the cylinder and pins) is pushed on to the pins and the reduced nose portions 2a thereof project through the perforations in said plate 5 on to a jacquard card 12, and when a pin 2 registers with a perforation in the card, the reduced nose 2a of said pin projects through said perforation and the aforesaid shoulder portion 2b of the pin makes 10 facial contact with the contact plate 5. In doing this an electrical circuit is completed through a 15 suitable battery and the magnet 8 associated with said pin is energized. This causes a slidable catch element 13 (Fig. 2) to be drawn by the armature of the magnet 8 into a position projecting axially from the end of said magnet, and in 20 this projecting position the catch element 13 or a suitably shaped nose portion thereof comes into engagement with a notch 14 in the aforesaid 25 slidable notched bar 9 and, dependent upon the position of said notch, retains the picker 10 in 30 a position either wholly or partially withdrawn from the threads 15 of the machine. In other words, when the catch element 13 of the magnet 8 engages a notch 14 in the sliding bar 9, the resilient or springy picker 10 is held from 35 being operated by the picker cam 11. Those contact pins which do not register with perforations in the jacquard card 12 are pressed back by said card against their cushion springs 4 housed in the block 3, and the shoulder portions 35 2b of said depressed pins are maintained clear of the contact plate 5 and consequently do not 40 complete an electrical circuit; therefore the magnets associated with said pins are not energized, and the pickers associated with said magnets are operated in the customary manner by 45 the picker cam.

The connections between the several pickers 10 and their associated slidable notched bars 9 advantageously consist of comparatively short flexible 45 connections 16 covered or encased with cellulose or equivalent substance such as rubber for preventing said flexible connections being adversely affected by atmospheric conditions. It will, of course, be appreciated that by connecting 50 the notched bars to the pickers with flexible connections, positive means must be provided for automatically returning the sliding bars 9 to their normal position after each operation by the picker cam 11, and this is conveniently effected by forming each notched bar with a downturned lug or projection 17 at its inner end and by providing 55 adjacent to said downturned portions a horizontal rocking shaft 18 with upwardly projecting blade 19 which, at each motion of the machine, 60 coacts with said downturned portions 17 and positively pushes back those of the notched bars 9 which have been displaced by the picker cam, (Fig. 1). The notched bars may be slidably 65 mounted in spaced upstanding flanges or edge portions 20 of a metal bed 21 which constitutes a carrier for the several electro-magnets 8.

70 Preferably, the magnets are arranged in a close and compact nest. For example, same may be arranged in four or more rows, (eight rows being shown) one closely behind the other, the disposition of the magnets across the bed 21 being diagonal and the arrangement being such as to cause individual catch element 13 to act with 75 separate notched bars. Advantageously the mag-

nets are located below the notched bars 9 so that when energized, the catch elements are lifted into engagement with said bars and when de-energized said elements automatically fall by gravity out of engagement with the bars. If desired, however, the magnets may be located above the bars, as represented in Fig. 9 and the contact elements may comprise short pins with hook-like extremities 13' which pass round and beneath the bars in such a manner that when a magnet is energized the hooked end of its pin is lifted into engagement with a notch, and when de-energized said pin end falls out of engagement with the notch and permits free sliding movement of the bar.

To enable what is known as full lift and half lift motion to be imparted to the pickers 10 at will each slidable notched bar 9 is provided with two notches 14 substantially close to each other, 20 the magnets 8 being operated so that the catch elements 13 thereof can be brought into engagement with either of said notches at will or maintained out of engagement with both notches; the provision of two notches enabling the pickers to 25 be held fully withdrawn from the threads 15 or in a position projecting partly through the threads, say for example beyond the first series of threads through which the pickers pass. When magnets are de-energized the pickers 10 30 associated with said magnets are moved by the picker cam 11 to the full extent between all the threads.

The variable adjustment of the pickers is obtained by employing a pair of jacquard cylinders 35 1, Fig. 1, and in one arrangement one of the jacquard cylinders is moved towards the contact pins 2 at the time the second cylinder is being moved away from same. One jacquard cylinder, which may be called the first cylinder, governs 40 the full lift, i. e. the complete withdrawal from the threads of the pickers, as the catch elements 13 of the armatures of the magnets controlled from said cylinder are, at the time of engagement between the cylinder and contact pins, located directly beneath the first of the two notches 14 in the slidable bars 9 (i. e. the notches nearest to the pickers) when said bars are fully withdrawn. Thus when nose portions 2a of contact 45 pins 2 enter perforations in a jacquard card 12 of the first cylinder and make contact with the contact plate 5 thereof, the selected magnets appertaining to said pins are energized and the selected pickers are maintained fully withdrawn, and held from operation by the cam 11.

The second jacquard cylinder governs the half lift motion of the pickers, as the armature catch elements of the magnets controlled from said second cylinder are, when the cylinder is moved on to the contact pins, located directly beneath the second of the two notches 14 in the slidable bars 9 (the notches farthest removed from the pickers). Thus when producing half motion or half lift of selected pickers, nose portions 2a of contact pins 2 coact with an imperforate part of 50 a jacquard card on the first cylinder and with a perforation in a card on the second cylinder.

When pickers are operated to go right through the threads by the customary picker cam 11, the magnets associated with said pickers are not energized, and the noses of contact pins controlling said magnets coact with blank or imperforate parts of cards on both cylinders.

The manner in which the three motions, i. e. the full lift, half lift and right through motions, 55 of the pickers 10 are obtained will be more clear-

ly understood by reference to Figures 6, 7 and 8. In Figure 6 the full lift motion is shown, this being governed by the first or right hand jacquard cylinder 1. When this cylinder moves inwards the nose portion 2a of the contact pin 2 passes through a perforation in the jacquard card 12 and enters a perforation 1a in the jacquard cylinder, and in so doing electrical contact is made between the shoulder 2b of the contact pin and the contact plate 5 and the magnet 8 is energized to cause the magnet catch or core 13 to enter the first of the two notches 14 in the slidable bar 9, thereby maintaining the picker 10 fully withdrawn from the threads 15. The subsequent motion of the second jacquard 20 cylinder (left hand cylinder) has no effect on the picker seeing that the corresponding contact pin appertaining to this cylinder coacts with an imperforate part of the jacquard card on said cylinder.

In Figure 7 the half lift motion is illustrated, this being effected at the second or left hand jacquard cylinder. Here the motion of the first cylinder does not energize the magnet seeing that the jacquard pin coacts with an imperforate part 25 of the jacquard card. At the second cylinder, however, the contact pin coacts with a perforation in the jacquard card and in the manner before described energizes the magnet 8 to bring its catch element 13 into engagement with the second of the two notches 14 in the sliding bar 9 and cause the picker 10 partly to enter the threads 15, e. g. pass between the first line of said threads. It is understood that the energization 30 of the magnet is timed to engage the second of the two notches 14.

In Figure 8 is illustrated the manner in which the right through position of the picker is obtained, this being effected by causing an imperforate part 35 of the jacquard cards on both jacquard cylinders to engage with the contact pins coacting with said cylinders, thereby preventing magnet energization and causing the picker to be projected by the customary picker cam right 40 through the threads 15.

Although for the sake of clearness the jacquard cylinders are in Figs. 6, 7 and 8 both shown in the inner or operative positions coacting with the contact pins, it will be appreciated that in 45 actual operation the cylinders are operated alternately, the one or right hand cylinder moving into the picker selecting and operating position before the other or left hand cylinder.

The movement of the jacquard cylinders may 50 be effected in the well known manner through bell crank lever mechanism so as to move in opposite directions to and from each other.

Each contact plate 5 is maintained dead until all the contact pins 2 that are required make 55 contact (i. e. that coact with perforations in a jacquard card) have their annular shoulders 2b well pressed on to the plate, when the current is automatically switched on at the exact required time by the closing of a switch or contacts as indicated at c in Fig. 2. The facial contact between the shoulders 2b and the plates 5 eliminates or minimizes the danger of dust or the like preventing effective contact.

The wires extending from the contact pins 2 60 may extend directly to the magnets 8. Preferably, however, the electrical connection between the pins 2 and the magnets is effected 65 through the intermediary of an electric current distributing device. The main purpose of this 70 75

is to enable any desired width of fabric to be produced and consequently also to enable the pickers or jacks in a machine of any desired width to be controlled by the use of jacquard cards of minimum size, said distribution device 5 enabling one or more magnets and consequently also one or more pickers to be controlled and operated at will from one and the same contact element at the jacquard. In other words, fabric 10 of any predetermined width can be produced with a card considerably smaller than would be required with the customary string type machine. For instance, cards of a size necessary for controlling the pickers in a lace curtain machine for 15 producing a division or width of fabric of say 40 inches can, by the employment of the distribution device, also be employed for producing fabric two or more times this width, the pattern determined by the punching of the cards being electrically duplicated or multiplied across the full 20 width of the machine.

The distribution device may comprise two contact plates 22, 23 (Fig. 2) of insulating material. The rear plate 22 is fitted with a series of spring- 25 pressed contacts 24 slidably assembled within holes extending through the plate. The front plate 23 is detachably attached over the face of the rear plate by bolts and nuts 25 or other convenient means and is fitted with a series of 30 screw contacts or other suitable contacts 26 which, when the two plates are assembled one upon the other, project into the holes in the rear plate 22 and depress the contacts 24. The contact pins 2 of the jacquard are electrically 35 connected by wires to an equal number of contacts 24 grouped at one part or section of the rear plate 22, say for example at the left hand side thereof, and said contacts 24 of this group are also electrically connected with the magnets 40 appertaining to the pickers extending across a predetermined width of the machine. This group of contacts 24 is duplicated or multiplied across the plate 22, and a corresponding group of contacts 26 co-operating with the said group of contacts 24 is also duplicated or multiplied across 45 the front plate 23. The co-operating contacts 24, 26 appertaining to the group or groups additional to the first named group are not, however, directly connected to the jacquard pins 2, but each contact 26 of the first group on the 50 plate 23 is electrically connected to a corresponding contact 26 of the second group and so on throughout the several groups on said plate 23. The contacts 24 appertaining to the group or groups additional to the first group on rear plate 22 are not, however, electrically connected with those of said first group as is the case with the contacts 26 on plate 23 but are individually wired 55 to magnets along the machine.

60 Let it be assumed that fabric is being made on an eight point curtain machine, and that there are 320 contacts 24 in the first group on plate 22 of the distributor directly connected to an equal number of pins 2 at the jacquard and to an equal 65 number of magnets and pickers in the machine to produce a 40 inch width or division of fabric. Individual contacts 26 in the first group on plate 23 co-operating with the contacts 24 of the first group on plate 22 are wired to individual contacts of the second group on said plate 23, and those of the second group are similarly wired to the contacts of the third group and so on.

If now an 80 inch width (two 40 inch divisions) of fabric is to be made, the front contact plate 70 23 of the distributor has its contacts 26 so wired

or arranged as to bring into circuit the contacts 24 of both the first and second groups on plate 22, and in this manner the number of magnets and pickers operated or controlled from the jacquard by the same cards is doubled, and the contacts 24 appertaining to the second group on plate 22 are, through the contacts on the front plate 23, electrically connected to a second group of magnets and pickers.

It will, therefore, be appreciated that each 10 division of fabric is duplicated or multiplied at the distributor, and the wiring of said distributor can be varied to accommodate manufacturers' varying requirements. It will also be appreciated that one predetermined size of jacquard 15 card (considerably smaller than the card at present employed) can be used on machines of different widths for making fabric of different widths, the patterns being duplicated across the machine.

Another advantage gained by the present invention is that, by virtue of being able to employ a comparatively small jacquard, no reduction in speed of operation of the machine is necessary when transferring to what are known as jacked classes of work from ordinary work.

Advantageously the wiring of the front contact plate 23 of the distributor is enclosed or shielded by a cover plate 21 which is detachable from said front plate.

The several wires extending to and from the 30 distributor may be gathered together in one or more groups or bunches and extend through one or more tubes or sheaths. Also means are advantageously provided for preventing any sparking at the jacquards, i. e. between the contact 35 pins and plates.

This can be effected by the insertion of a condenser in the circuit between the jacquard contacts and the distributor.

I claim:—

1. A textile machine, e. g. a lace curtain machine, embodying in combination a series of pickers or jacks co-operating with threads such as spool or warp threads to determine the character of fabric produced, a series of electro-magnets associated with said pickers, jacquard mechanism with co-operating perforated jacquard cards, electric contact elements co-operating with perforations in the jacquard cards and functioning by such co-operation selectively to energize the electro-magnets, an electric current distributor between the jacquard and the magnets functioning to distribute the electric current to the magnets in such a manner that the number of contacts simultaneously operated can be in excess of the number of operative contact elements at the jacquard and the character of the fabric being produced can be increased without increasing the size of the jacquard cards or the perforated area thereof. 60

2. A textile machine according to claim 1 wherein the electric current distributor has a number of contacts in excess of the number of contacts at the jacquard, and the contacts of the distributor are connected or wired one with another and electrically connected with the magnets in such a manner as to enable a single contact at the jacquard to operate a plurality of magnets and consequently also a plurality of pickers controlled thereby.

3. A textile machine, e. g. a lace curtain machine embodying in combination a series of pickers or jacks co-operating with shogged threads in the machine, said pickers being normally held clear of the threads, a cam operating normally 75

to project the pickers between the threads, a 5
slidable bar connected to and movable with each
picker, each bar having a plurality of spaced
notches, a series of electro-magnets associated
one with each picker, a catch associated with
each electro-magnet, a jacquard mechanism em-
bodying rotary cylinders, perforated jacquard
cards traversing said cylinders, an electric con-
tact plate associated with each jacquard cyl-
inder, contact pins selectively making contact
with said contact plate by virtue of the per-
forations in the jacquard cards and by so doing
selectively energizing the magnets, the catch
elements associated with the magnets co-operat-
ing with the notched slidable bars in such a
manner that the pickers can take up one of
three positions in relation to the threads, i. e.
"right through", "partly through" or "clear" of
the threads, an electric current distributor in-
corporated between the jacquard contacts and
the electro-magnets, said distributor embodying
a number of interchangeable contact plates so
wired as to control a varied number of magnets
and functioning to enable the number of mag-
nets and associated pickers operated by the jac-
quard to be duplicated, increased without in-
creasing the number of contacts at the jacquard
or the number of perforations in the jacquard
cards.

30 4. A textile machine according to claim 1
wherein an electric current distributor is pro-
vided with a series of contacts the number of
which is in excess of the number of contacts at
the jacquard, said distributor contacts being
35 individually connected to the electro-magnets

and being wired together in groups in such a
manner that the contacts of one group are elec-
trically connected with the jacquard contacts
and the distributor contacts appertaining to a
plurality of said groups can be brought into cir-
cuit to control a number of magnets and pick-
ers in excess of the number of contacts at the
jacquard.

5 5. A textile machine according to claim 1
wherein the electric current distributor com-
prises two plates detachably assembled one upon
another, one plate carrying a series of spring-
pressed electrical contacts and the second plate
carrying other contacts adapted to coact with
those of the first plate, and the contacts of 15
either or both of said plates being so wired or
electrically connected one with another as to en-
able a number of picker controlling electro-
magnets in excess of the number of contacts
coacting with a jacquard card at any given time 20
to be brought into circuit as desired.

6. A textile machine according to claim 3
wherein the notched bars associated with the
electro-magnets are, after each motion of the
machine, operated upon by a rocking bar which 25
returns all of the notched bars to their inoper-
ative position.

7. A textile machine according to claim 3
wherein each of the notched bars associated
with the electro-magnets is connected to a 30
picker or the like by a flexible connection cov-
ered or encased with material or substance
which is not effected by atmospheric conditions.

HARRY GOODLEY. 35
